US0D1093986S

(12) **United States Design Patent** (10) **Patent No.:** **US D1,093,986 S**
(45) **Date of Patent:** **** Sep. 23, 2025**

(54) **PIZZA GRILL BAKER**

(71) Applicant: **Chengru Dai**, Chuzhou (CN)

(72) Inventors: **Rongchang Fang**, Yueyang (CN);
Chengru Dai, Chuzhou (CN)

(73) Assignee: **Chengru Dai**, Chuzhou (CN)

(**) Term: **15 Years**

(21) Appl. No.: **29/947,404**

(22) Filed: **Jun. 14, 2024**

(30) **Foreign Application Priority Data**

May 16, 2024 (CN) 202430290668.9

(57) **CLAIM**

The ornamental design for a pizza grill baker, as shown and described.

DESCRIPTION

FIG. 1 is a front, left and top perspective view of a pizza grill baker, showing our new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the pizza grill baker that form no part of the claimed design.

1 Claim, 8 Drawing Sheets
